UNITED STATES PATENT OFFICE.

SAMUEL GARRE, OF BROOKLYN, ASSIGNOR TO OBPACHER BROTHERS, OF NEW YORK, N. Y.

DESIGN FOR A FANCY CARD.

SPECIFICATION forming part of Design No. 13,170, dated August 8, 1882.

Application filed July 11, 1882. Term of patent 3½ years.

To all whom it may concern:

Be it known that I, SAMUEL GARRE, of Brooklyn, in the county of Kings and State of New York, have invented a new and original 5 Design for Fancy Cards, of which the following is a full, clear, and exact description, reference being had to the accompanying drawing, which makes a part of this specification, and which fully shows the nature of my de- 10 sign.

The object of my invention is to furnish an improved design of fancy card for Christmas and other purposes; and it consists of a main part in the form of a palette provided with 15 raised puffs, and with an interior raised center panel for a picture or other suitable ornamentation, and with a tie passing through the opening of the palette-shaped main part.

Referring to the drawing, A represents the 20 body of my improved fancy card, which is made of stiff paper or pasteboard and cut in the shape of a palette, with the usual opening, a, for the thumb. The body A is covered with silk or other suitable fabric and provided with 25 a silk fringe, B, along its outer circumference. A raised panel, C, is arranged at the center of the main portion A, and made to correspond in its general shape therewith. This panel C is ornamented in any suitable manner, accord- 30 ing to the object for which the fancy card is designed. At one side of the center panel, C, are arranged a number of raised tufts, D, of raw silk or other suitable material, which tufts are 35 preferably made in different colors, so as to imitate the spots of color applied by painters

to the palette. A tie, E, of silk or other material, is applied to the card by being passed through the thumb-opening a of the main portion A and panel C, so as to give the appearance of connecting them together. The tie E 40 imparts a certain finish to the card, which forms an elegant ornament for the mantelpiece, and is suitable for Christmas, Easter, and other occasions.

Having thus described my invention, I claim 45 as new and desire to secure by Letters Patent—

1. The design for a fancy card, consisting of a palette-shaped main part or body, A, of a raised ornamented center panel, C, and of raised tufts D at one side thereof, substan- 50 tially as shown and described.

2. The design for a fancy card, consisting of a palette-shaped main part or body, A, having an exterior fringe, B, of an interior raised and ornamented panel, C, and of raised tufts 55 D of different colors between the panel and fringe, substantially as shown and described.

3. The design for a fancy card, consisting of a fringed palette-shaped body, A, a raised interior panel, C, raised tufts D at one side 60 thereof, and a tie, E, passing through the thumb-opening a of the main part and panel, substantially as shown and described.

In testimony that I claim the foregoing as my invention I have signed it this 24th day of 65 June, 1882.

SAMUEL GARRE.
